TRACK INSTRUMENT

Frank H. Richterkessing, Louisville, Ky., assignor to Nachod & United States Signal Co., Incorporated, Louisville, Ky., a corporation of Kentucky

Application March 3, 1941, Serial No. 381,449

5 Claims. (Cl. 200—1)

This invention relates to improvements in a rail-operated circuit-controller, sometimes referred to as a track instrument.

The primary object of this invention is to provide a track instrument operated by the vertical movement of a rail or track for opening or closing a circuit by the passage of a car or train over the rail at the location of the instrument.

Another object of this invention is to provide a track instrument in which the depression of the rail is transmitted to the contacts of the instrument by means of a self-adjusting friction-drive.

A further object of this invention is to provide a track instrument having means for adjusting the actuating lever thereof, so as to accommodate various ranges of rail movements.

Another object of this invention is to provide a track instrument having biasing means, operatively associated with the contact mechanism thereof, for automatically actuating the contact mechanism to a position for a safe failure, should the actuating lever become accidentally disconnected from the rail.

A further object of the invention is to provide simple devices for adjusting the position of the instrument with respect to the rail.

Another object of my invention is to provide a simple contact mechanism, whereby the normally-open contacts close before the normally-closed contacts open.

These and other objects will manifest themselves as the following description is read in connection with the accompanying drawings, in which:

Figure 1 is a plan view of the instrument illustrating the relative position of the same with respect to the rail, and the manner in which the actuating lever 21 embraces the rail;

Figure 2 is a side elevational view of the instrument also illustrating the relative position of the same with respect to the rail, and the manner in which the actuating lever 21 embraces the rail;

Figure 3 is a sectional view on a slightly enlarged scale and taken along line 3—3 of Figure 8.

Figure 4 is an enlarged detail of the contact mechanism, illustrating the relation of the parts when the actuating lever 21 of Figure 3 is raised by the rail;

Figure 5 is an enlarged detail of the contact mechanism, illustrating the relation of the parts when the actuating lever 21 of Figure 3 is depressed by the rail;

Figure 6 is a front elevational view of the instrument;

Figure 7 is a plan view of the instrument with the cover removed; and

Figure 8 is a front elevational view of the instrument with the cover removed.

This invention has particular reference to improvements in track instruments of the class disclosed in my United States Letters Patent No. 2,128,164 issued August 23, 1938, and entitled "Rail operated circuit controller." Accordingly, to coordinate the disclosure of my present invention with that embraced by the aforesaid letters patent, all similar parts and apparatuses of my present invention have been designated by corresponding numerals and characters.

Referring now in detail to the accompanying drawings illustrating the present invention, it will be observed that the contact mechanism is mounted within a casing 10 having a removable cover 13. As illustrated in Figure 2, the instrument casing 10 and cover 13 separate along a diagonal line to provide complete access to the operating parts within the casing 10, when the cover 12 is removed. While not specifically illustrated in the drawings, it is to be understood that the cover 13 has a perimetrical ledge to which is secured a suitable gasket, which gasket is adapted to engage the diagonal edges of the casing 10 to provide a water-tight seal.

With reference to Figures 1 and 2, it will be observed that the cover 13 is removably secured to the casing 10 by means of a suitable clamping device, which device includes a link 60 pivotally secured to lugs 10c by means of a pivot pin 59. One end of an arm 62 is pivotally secured to link 60 by means of a pivot pin 61, and the opposite end of arm 62 is slotted to receive shank 66a of link 66. Link 66 is pivotally secured to lugs 10b by means of a pivot pin 68. A clamping nut 63 is threaded upon the threaded portion of shank 66a, which nut operatively engages the slotted end of arm 62 for clamping the arm against the cover 13.

To provide a uniform compression of the cover gasket, arm 62 is provided with a centrally-disposed conical-projection, which projection is guided into central engagement with the cover by means of a suitable conical depression formed therein. A hasp lever 65 is pivotally secured to the clamping nut 63 by means of a pivot pin 64, and the hasp lever is slotted to receive a suitable lock-receiving staple 67 fixedly secured to link 66.

The mechanism case 10 is also provided with

mounting lugs 10a, which lugs are slotted to receive clamping bolts 12 for adjustably securing the mechanism case 10 to an adjustable foundation.

The adjustable foundation, as shown in Figure 2, includes a top plate 11 having an aperture receiving a center tube 69. The upper end of center tube 69 is fixedly secured to plate 11, as for instance, by welding, and the tube 69 slides within a stationary tube 70. The stationary tube 70 is preferably long enough to extend below the frost line, and is provided with an enlarged footing or base plate. The upper end of the stationary tube 70 is slotted longitudinally, and, by means of clamp 72, U-bolt 71 and nuts 73, the stationary tube 70 is clamped to the center tube 69 for securing the same in various positions of vertical adjustment. The stationary tube 70 is also apertured near the base plate, and all external wiring enters the latter mentioned aperture and extends upwardly through the tubes and into the mechanism case 10 by means of a coupling 40.

The coupling 40 comprises a short length of conduit secured to the mechanism case by means of locknuts 40a and suitable gaskets. The external wiring is brought into the mechanism case through the short length of conduit, which wiring is sealed in the conduit by means of suitable compound. Accordingly, it will be apparent that the coupling 40 becomes a part of the external cable or wiring, which coupling in turn is detachably secured to the mechanism case by means of the aforesaid locknuts 40a, as illustrated in Figure 8.

As further illustrated in Figure 2, the instrument is preferably mounted between two adjacent ties 75, and adjacent the base of the rail 24, with the rigid rail arm 21 on top of the rail base, and the rail spring 22 beneath the rail base. Therefore, it will be apparent that the relative vertical movement of the rail with respect to the earth or ballast 76 is transmitted to the contact mechanisms within the instrument, via the rail arm 21 and rail spring 22.

As illustrated in Figure 6, rail arm 21 is provided with 3 apertures, either of which may receive the shaft 19, and thus provide three operating lengths for the rail arm 21. A pair of clamping bolts 23 are provided for securing the rail arm 21 to the shaft 19.

As illustrated in Figure 3, shaft 19 is journaled in boss 17, which boss is fixedly secured to casing 10. At 19c the shaft 19 is reduced in diameter to provide a chamber for receiving lubrication via a lubricating fitting 53 shown in Figures 1, 2 and 7.

A suitable packing material 42 surrounds shaft 19, which material is retained in a suitable packing cup by means of a packing gland 43.

A mechanism plate 25 is journaled on shaft 19, which mechanism plate 25 is provided with an annular recess for receiving a friction disc 26, preferably made of sheet cork, and a drive plate 20.

As illustrated in Figure 3, the shaft 19 is reduced in diameter at 19a, and straight-knurled for fixedly securing the drive plate 20 to shaft 19. An extension 57 is fixedly secured to the reduced portion 19a by means of rivet 19b, and an arm 48 is adjustably secured to the extension 57 by means of set screw 50. The extension 57 is also reduced in diameter at 57a, so that any burring of the extension 57 by means of set

screw 50 will not interfere with adjustment or removal of arm 48.

A spring collar 27a is journaled on shaft 19, likewise the packing gland 43, and a compression spring 27 reacts between the packing gland 43 and collar 27a for compressing the friction disc 26 between the drive plate 20 and mechanism plate 25, and for compressing the packing material 42.

10 A thrust collar 53 is removably secured to shaft 19 by means of a tapered pin 54, which collar engages boss 17 for limiting the longitudinal inward movement of shaft 19. Accordingly, it will be apparent that the rail arm 21 can 15 be removed without disassembling the mechanism carried by shaft 19.

Obviously, rotation of shaft 19, via rail arm 21, correspondingly rotates drive plate 20, the rotation of which, rotates the mechanism plate 25 20 about the axis of shaft 19 via friction disc 26.

To limit the rotational movement of mechanism plate 25, a post 29 is fixedly secured at 29a to the casing 10. A pivot pin 28 is fixedly secured in post 29, which pin extends through an 25 aperture 25a in the mechanism plate 25.

As illustrated in Figures 4 and 5, the diameter of aperture 25a is greater than the diameter of the pivot pin 28, and thus permits rotation of the mechanism plate 25 in accordance with the 30 limits determined by the difference in diameter of aperture 25a and pivot pin 28.

The drive plate 20 and mechanism plate 25 are preferably made of insulating material, and a contact 32 is fixedly secured to the mechanism 35 plate 25, preferably on the side opposite to that having the aperture 25a, and preferably between the aperture 25a and the pivotal axis of the mechanism plate 25.

A contact block 77, preferably constructed of 40 insulating material, is journaled on pivot pin 28 and drive pin 25b. Accordingly, it will be apparent that rotation of drive pin 25b about shaft 19 correspondingly rotates contact block 77 about pivot pin 28. Obviously, therefore, clockwise rotation of mechanism plate 25 about shaft 19, provides a counter-clockwise rotation of the contact block 77 about pivot pin 28.

A flexible contact member 34 is fixedly secured 45 to the contact block 77 via screws 47, which flexible member is provided with a contact plate 33 adapted to electrically engage contact 32, when the mechanism plate 25 is rotated in a counter-clockwise direction. A rigid contact-member is also fixedly secured to the contact block 77 via 55 screws 48, which rigid member is provided with a contact tip 31a adapted to mechanically and electrically engage the contact plate 33, when the mechanism plate 25 is rotated in a clockwise direction.

60 From the foregoing it will be apparent that counter-clockwise rotation of the mechanism plate 25 about shaft 19, provides a clockwise rotation of the contact block 77 about pivot pin 28 via drive pin 25b. Accordingly, contact plate 33 and contact 32 each move one toward the other and into electrical engagement. The rigid member 31, flexible member 34 and contact 32 are so 65 related one to the other that contact plate 33 and contact 32 electrically engage, and contact tip 31a and contact plate 33 disengage substantially at the midpoint of the rotational movement of the mechanism plate 25.

Therefore, further counter-clockwise rotation 70 of the mechanism plate 25 flexes member 34, and

moves the contact tip 31a further from engagement with contact plate 33.

Figure 5 illustrates the relation of parts at the extreme limit of counter-clockwise rotation of mechanism plate 25, and Figure 4 illustrates the relation of parts at the extreme limit of clockwise rotation of mechanism plate 25.

Obviously, clockwise rotation of the mechanism plate moves the contact tip 31a into engagement with the contact plate 33 substantially at the mid-point of its rotational movement, thereby electrically engaging contacts 31a and 33, and electrically disengaging contacts 33 and 32, whereupon further clockwise rotation of mechanism plate 25 moves contact plate 33 further from engagement with contact 32.

As illustrated in Figure 8, a terminal board 38 of insulating material is fixedly secured to casing 10 via screws 39, which terminal board is provided with three terminal posts 36, 37 and 46 to which terminals the external wiring connections are made.

As further illustrated in Figures 4, 5 and 8, flexible wire-connection 36a connects terminal 36 and rigid member 31; flexible wire-connection 37a connects terminal 37 and flexible member 24; and flexible wire-connection 46a connects terminal 46 and contact 32.

As illustrated in Figures 3, 7 and 8, a tension spring 78 connects arm 49 and hook 52, which hook is fixedly secured to casing 10. A similar hook 51 is also provided at the opposite side of the pivotal axis of arm 49, so that spring 78 and arm 49 may be adapted to rotate the mechanism plate 25 either in a clockwise or counter-clockwise direction should the rail arm 21 become accidentally disconnected from the rail.

As illustrated in drawings, spring 78 and arm 49 are adapted to rotate the mechanism plate 25 in a clockwise direction should the rail arm 21 accidentally disengage the rail.

Similarly, it will be observed that the drawings illustrate the rail arm 21 disposed to provide a counter-clockwise rotation of the mechanism plate 25 in response to a downward movement of the rail, and a clockwise rotation in response to an upward movement of the rail. Obviously, as illustrated in dotted lines in Figure 1, the position of rail arm 21 may be reversed so that a downward movement of the rail provides a clockwise rotation of the mechanism base 25, and an upward movement of the rail provides a counter-clockwise rotation of the mechanism plate 25.

With the rail arm 21 disposed as illustrated in solid lines in Figure 1, the mechanism plate 25, and associated parts, normally assume the relative positions illustrated in Figure 4, which parts are moved to the relative positions illustrated in Figure 5 in response to a downward movement of the rail with respect to the earth or ballast 76.

Obviously, with the rail arm disposed as illustrated in dotted lines in Figure 1, the mechanism plate 25, and associated parts, normally assume the relative positions illustrated in Figure 5, which parts are moved to the relative positions illustrated in Figure 4 in response to a downward movement of the rail with respect to the earth or ballast 76.

Operation

Assuming the rail arm disposed in the position illustrated in solid lines in Figure 1, and the spring 78 and arm 49 disposed as illustrated in Figure 8, the mechanism plate and associated parts will assume the relative positions illustrated in Figure 4, when the rail 24 is in the normal position illustrated in Figure 2.

Accordingly, a train moving past the point including rail 24, moves the rail downwardly with respect to the earth or ballast 76.

5 This downward movement of rail 24, rotates the mechanism plate 25 in a counter-clockwise direction, via rail arm 21, shaft 19, drive plate 20 and friction disc 26.

10 Counter-clockwise rotation of the mechanism plate 25 about shaft 19, rotates contact block 77 clockwise about pivot pin 28, via drive pin 25b.

15 Clockwise rotation of the contact block 77 about pin 28, brings contacts 32 and 33 into electrical engagement, and contacts 33 and 31a out of electrical engagement.

Obviously, rotation of the mechanism plate, and associated parts, is limited by the inter-engagement of pin 28 and the walls of aperture 25a. 20 Accordingly, rotation of rail arm 21 in excess of that determined by pin 28 and aperture 25a, provides a slipping of the clutch formed by the drive plate 20, friction disc 26 and cooperating recess in the mechanism plate 25.

25 Therefore, as the train moves beyond the point including rail 24, the rail moves upwardly and restores the mechanism plate 25 and associated parts to their normal positions.

With spring 78 and arm 49 disposed as illustrated in Figure 8, the contacts 33 and 32 remain disconnected in the event the rail arm 21 accidentally disengages the rail 24. However, if it is desired to have the contacts 33 and 32 close upon such accidental disengagement, then the arm 49 is moved to the side opposite to that illustrated, and spring 78 connected to hook 51.

Having thus described my invention, I claim:

1. A switch instrument comprising, a stationary frame; a first base of insulating material rotatably mounted on said frame; means for rotating said base in one or the opposite direction, respectively; a first contact fixed to said base at one side of the axis of rotation of said base; said base having an aperture therein at the opposite side of the said axis of rotation; a stationary member fixed to said frame and projected through said aperture for limiting rotation of said first base; a second base of insulating material rotatably mounted on the said member; a second contact fixed to said second base; a third contact flexibly mounted on said second base and electrically engaging the said second contact; said first contact rotatable with the said first base and adapted to electrically engage the said third contact and to move the said third contact out of electrical engagement with the said second contact when the said first contact engages the said third contact; and a pin fixed to the said first base, and operatively associated with the said second base between the axis of rotation thereof and the axis of rotation of the said first base, for rotating the said second base to move the said first and third contacts into or out of electrical engagement, when the said first base is rotated in one or the opposite direction, respectively.

2. A switch instrument comprising, a stationary frame; a first base of insulating material rotatably mounted on the said frame; means for rotating the said first base in one or the opposite direction respectively; an operating member fixed to said base at one side of the axis of rotation thereof; said base having an aperture therein at the opposite side of the axis of rotation thereof; a stationary member fixed to said frame and projected through said aperture for

limiting rotation of said first base; a second base of insulating material rotatably mounted on the said stationary member; a first contact fixed to said second base; a second contact flexibly mounted on said second base and electrically engaging the said first contact; the said operating member rotatable with the said first base and adapted to engage the said second contact and to move the said second contact out of electrical engagement with the said first contact, when the said operating member engages the said second contact; and a pin fixed to the said first base, and operatively associated with the said second base between the axis of rotation thereof and the axis of rotation of the said first base, for rotating the second base to move the said second contact and the operating member into or out of engagement, when the said first base is rotated in one or the opposite direction, respectively, thereby to move the said first and second contacts into or out of electrical engagement.

3. A switch instrument comprising, a stationary frame; a first base of insulating material rotatably mounted on the said frame; means for rotating the said first base in one or the opposite direction, respectively; means fixedly secured to the said frame, and operatively associated with the said first base, for limiting rotation of the said first base; an operating member fixed to the said first base at one side of the axis of rotation thereof; a second base of insulating material rotatably mounted on the said frame and at the opposite side of the axis of rotation of the said first base; a first contact fixed to the said second base; a second contact flexibly mounted on the said second base and electrically engaging the said first contact; the said operating member rotatable with the said first base and adapted to engage the said second contact and to move the said second contact out of electrical engagement with the said first contact, when the said operating member engages the said second contact; and means fixedly secured to said first base, and operatively engaging the said second base between the axis of rotation thereof and the axis of rotation of the said first base, for rotating the said second base to move the said second contact and the said operating member into or out of engagement, when the said first base is rotated in one or the opposite direction, respectively, thereby to move the first and second contacts into or out of electrical engagement.

4. A switch instrument comprising, a stationary frame; a first base of insulating material rotatably mounted on said frame; means for rotating the said first base in one direction; means fixedly secured to the said frame, and operatively asso-

ciated with the said first base, for limiting rotation of the said first base; a first contact fixed to the said first base at one side of the axis of rotation thereof; a second base of insulating material rotatably mounted on the said frame and at the opposite side of the axis of rotation of the said first base; a second contact fixed to the said second base; a third contact flexibly mounted on the said second base and electrically engaging the said second contact; the said first contact rotatable with the said first base and adapted to electrically engage the said third contact and to move the said third contact out of electrical engagement with the said second contact, when the said first base is rotated in one direction; means fixedly secured to the said first base, and operatively engaging the said second base between the axis of rotation thereof and the axis of rotation of the said first base, for rotating the said second base to move the said third contact into electrical engagement with the said first contact and out of electrical engagement with the said second contact; and a spring secured to the said frame and operatively associated with the said first base, for moving the said first base in the opposite direction to move the said third contact out of electrical engagement with the said first contact and into engagement with the said second contact.

5. A switch instrument comprising, a stationary frame; a first base of insulating material rotatably mounted on said frame; means for rotating the said first base in one or the opposite direction, respectively; means fixedly secured to the said frame, and operatively associated with the first base, for limiting rotation of the said first base; a first contact fixed to the said first base at one side of the axis of rotation thereof; a second base of insulating material rotatably mounted on the said frame and at the opposite side of the axis of rotation of the said first base; a second contact fixed to the said second base; a third contact flexibly mounted on the said second base and electrically engaging the said second contact; the said first contact rotatable with the said first base and adapted to electrically engage the said third contact and to move the said third contact out of electrical engagement with the said second contact; and means fixedly secured to the said first base, and operatively engaging the said second base between the axis of rotation thereof and the axis of rotation of the said first base, for rotating the said second base to move the said third contact into electrical engagement with the said first contact and out of electrical engagement with the said second contact.

FRANK H. RICHTERKESSING.
